S. PENKSA

DUPLICATE TAG

Filed Nov. 20, 1920

Stanley Penksa INVENTOR.

UNITED STATES PATENT OFFICE.

STANLEY PENKSA, OF LONG ISLAND CITY, NEW YORK.

DUPLICATE TAG.

Application filed November 20, 1920. Serial No. 425,502.

To all whom it may concern:

Be it known that I, STANLEY PENKSA, a citizen of the United States, residing at Long Island City, in the county of Queens and State of New York, have invented certain new and useful Improvements in Duplicate Tags, of which the following is a specification.

This invention relates to improvements 10 in shipping tags and has for its object to provide a pair of duplicate tags and means whereby said tags are held together.

Another object of the invention is to provide a pair of duplicate shipping tags two 15 of the ends of which are fixedly secured together, and the other ends of which are removably held together.

With the above and other objects in view I have invented the device illustrated in the 20 accompanying drawings in which,

Figure 1 is a plan view of my improvement in shipping tags,

Figure 2 is another plan view thereof,

Figure 3 is a longitudinal central sec- 25 tional view thereof, and

Figure 4 is a perspective view of the device, certain ends of the tag being shown separated.

It is well known that shipping tags used 30 on packages, boxes, barrels, crates, etc., often become mutilated through rain or other causes, whereupon the package to which the tag is secured has no identification mark to indicate its destination or 35 from whence it came. Therefore I have designed the tag shown in the accompanying drawings in order that the addresses of both the sender and the party to whom the package is to be sent may be shown in duplicate; that is, on both of the tags, so if one 40 becomes mutilated it may be removed and the addresses are still indicated on the other.

A further object of the device is in order 45 that the addresses may be printed on the outer sides of the duplicate tags, and instructions may be printed on the inner sides thereof, or the inner sides may have return addresses printed thereon if the package or container should be returned to the original shipper, thus insuring a correct return 50 address.

In the accompanying specification and drawings like reference characters indicate 55 like parts in which 1 indicates a shipping tag formed of two duplicate tags 2 and 3

fixed together at their small ends 4 by an eyelet 5. To the free end of the tag 3 is fastened an eyelet 6 and an elongated tongue 7 which is adapted to be bent over the edges 8 and 9 of the tags 2 and 3 respectively, whereby said tags are held together at their large ends 10 and 11. When it is necessary to examine the inner surface of the tags the tongue 7 may be readily straightened out to permit the separation of the tags at one end.

Having now described my invention that which I claim is new and desire to procure by Letters Patent is:

1. A device, as described consisting of a 70 pair of independent tags identical in size and form, an eyelet connecting said tags at one end and an eyelet secured to one of said tags at its free end said last eyelet having an elongated flexible tongue adapted 75 to be bent over the other tag, whereby both free ends of the tags may be held together.

2. A device as described consisting of a 80 pair of identically formed tags, means for pivotally connecting said tags at one end and means for detachably connecting the free ends of said tags, said last means consisting of an eyelet secured to the free end of one tag and having means for engaging 85 the free end of the other tag.

3. A device as described, consisting of a 90 pair of tags, an eyelet connecting said tags at one end and an eyelet having a tongue secured to one of said tags at the other end 90 and adapted to secure the other tag to said first tag.

4. A device as described consisting of a 95 pair of identically formed tags, means for pivotally connecting said tags at one end and means for detachably connecting the free ends of said tags, said last means consisting of an eyelet secured to the free end of one tag and having means for engaging 100 the free end of the other tag, said last means consisting of an elongated tongue integral with said eyelet and adapted to engage said other tag, said tongue being bendable over the free edges of both of said tags.

In testimony whereof I affix my signature in the presence of two witnesses.

STANLEY PENKSA.

Witnesses:

BENJAMIN BARKER,
CHAS. RUSSELL.
